UNITED STATES PATENT OFFICE.

ELMER R. CORWIN, OF CHICAGO, ILLINOIS, ASSIGNOR TO CORWIN TELEPHONE MANUFACTURING COMPANY, OF CHICAGO, ILLINOIS, A CORPORATION OF ILLINOIS.

TELEPHONY.

1,030,504.

Specification of Letters Patent. Patented June 25, 1912.

Application filed January 13, 1910, Serial No. 537,846. Renewed June 2, 1911. Serial No. 630,920.

To all whom it may concern.

Be it known that I, ELMER R. CORWIN, citizen of the United States, residing at Chicago, in the county of Cook and State of Illinois, have invented a certain new and useful Improvement in Telephony, of which the following is a full, clear, concise, and exact description, reference being had to the accompanying drawings, forming a part of this specification.

My invention relates to telephone systems wherein parties at substations may establish connections between the substations without the intervention of telephone exchange equipment, such systems being commonly known as intercommunicating systems or interior systems, it being understood that I do not limit myself to a system housed exclusively in one building.

My invention has a number of objects and advantages, in view among which are the provision of means whereby a party seeking connection with a line that is in telephonic connection with another or that is calling or is being called by another party is apprised of the condition of the line he seeks by means of a busy signal, and the provision of means for preventing telephone stations from being capable of telephonic connection with another telephone station which is calling or is in the process of being called or is in telephonic connection with another station.

I will explain my invention and further features thereof more fully by reference to the accompanying drawing showing the preferred embodiment thereof as applied to a system having three telephone stations, though I do not wish to be limited to the number of telephone stations that may be embodied in the system. The three stations are designated No. 1, No. 2 and No. 3, the telephone line extending from each of the stations being metallic, to which characteristic I do not wish to be limited. Station No. 1 thus has a metallic line 1 1 extending therefrom to each of the other stations. Similarly, station No. 2 has a telephone line 2 2 extending to each of the other stations, and station No. 3 has a telephone line 3 3 extending to each of the other stations. At each station there is a line selecting key α individual to each of the other lines, whereby each station may select any of the other stations, providing that the station to be

selected is free for selection. Each selecting key is also preferably adapted to cause the operation of the signal receiver at the selected station. In accordance with one novel feature of my present invention, each key, whether it is adapted to select or operate the signal receiver at the selected station or is adapted both to select and operate the signal receiver at the selected station, is also adapted to cause the manifestation of a busy signal in the event of selection of a station that is calling or has been called or is in connection with another. The circuits and apparatus by which the results above outlined are accomplished will be later explained.

There is an electro-magnet b at each station whose office is to establish communication between calling and called stations when the called station is free to be selected, the magnet b at the calling station being the one that is operated for this purpose. There is also an electro-magnet c at each station, such magnet at a calling station being operated when the called station is not free for selection for the purpose of establishing a busy test condition to apprise such calling station that the called station is not free for selection. The magnet c also serves to break or prevent the telephonic connection of the calling party that is endeavoring to select a called station that is not free for selection. The circuits and apparatus by which the magnets b c perform their functions will later be explained.

The system illustrated is a common battery system, to which however I do not wish to be limited. The common battery is illustrated at d . I preferably, though not necessarily, employ a source of current which is adapted to be used both for testing and for signaling, this source of current being illustrated at e . A circuit interrupting electro-magnet f is used for modifying the current from the battery e for testing purposes.

Having thus generally indicated some of the prominent characteristics of the system of my invention, I will now describe the embodiment of the invention illustrated more in detail.

In the drawing, station No. 1 is an original calling station, station No. 2 is a station that has been selected and called by station No. 1, station No. 2 having been free for selection, the magnet b at station No. 1 be-

ing free to operate telephonically to unite station No. 1 and station No. 2. Station No. 3 is a station which is illustrated in the act of endeavoring to select one of the other stations, station No. 1 in this instance. The station sought by station No. 3 not being free for selection, magnet *c* at station No. 3 is operated to prevent the connection of the telephone equipment at station No. 3 with the line that station No. 3 is endeavoring to select, magnet *c* at station No. 3 at the same time causing the manifestation of the busy condition of the line leading from station No. 1. The magnets *b* *c* at the selected 15 called station No. 2 are not operated.

The party at station No. 1 in initiating connection with station No. 2 first removes his telephone receiver *g* from his switch hook and thereafter fully depresses the button *a* at his station which is individual to line No. 2 extending from station No. 2, and under the assumption that station No. 2 is free for selection, the magnet *b* at station No. 1 is energized as a consequence of the 20 establishment of a circuit therethrough which may be traced from the upper terminal of the battery *d* through the impedance *i* in the line of the called station, in this instance line No. 2, the uppermost contact *a'* 25 of key *a* that is engaged by the contact *a''* connected with the upper side of the line 2 2 that includes the stated impedance *i* as a consequence of the full depression of the key *a* at station No. 1, thence through the 30 winding of magnet *b* to the switch hook *h* and the contact *h'* that is connected with the lower terminal of the battery *d* and which is engaged by the switch hook *h* at the calling station, the telephone receiver *g* having 35 been removed from said switch hook. The actuated key *a* at station No. 1 being still fully depressed, the extreme lower contact *e'* of said key (this contact being connected with the upper terminal of the battery *e*) is 40 connected with the lower limb 2 of the called line by way of contact *a'*, current from the battery *e* then finding path by way of the contacts *e' a'*, the lower side of the line 2 2 and the contacts *h' h'*, the circuit for this 45 current continuing from the signal receiver *l* to the lower side of the battery *e*, with which one terminal of said signal receiver is permanently connected. The called party at station No. 2, in response to the signal con- 50 tinued by the device *l* (this device being preferably in the nature of a direct current bell,) moves his telephone receiver from its switch hook. The calling party, after having maintained his actuated key *a* depressed 55 sufficiently long to operate the signal receiver *l* at the called station a proper length of time, releases the actuated key, which thereupon assumes the position illustrated, the springs engaging the key plunger and 60 forcing the plunger outwardly until the out-

ward movement is arrested by the pin *e* engaging the upper notch in the key. The position which the operated key at station No. 1 is initially caused to occupy is similar to the position occupied by the key *a* at station No. 3 that is individual to line 1 1. The pins *e* at each station are provided upon a common bar *e*, whereby when any key at a station is depressed, the pins *e* of such other station are released, the pins *e* of such other 70 keys occupying the innermost notches when the connecting bar rises, the return upward movement of the connecting bar being effected by spring mechanism *e*. The actuated key at the calling station continues in the position 75 in which it is illustrated throughout the remainder of the operations and until the bar *e* is again actuated either by the full depression of this key in case station No. 2 is again called by station No. 1 or until some other key at station No. 1 is depressed in case some other station is to be called. When the actuated key at station No. 1 is in the position shown, the top and bottom contacts are disconnected. The armature *k* belonging to the magnet *b* at station No. 1 is 80 attracted in a clockwise direction when circuit is closed through magnet *b* at station No. 1 to move the contacts *k'* which it carries into connection with contacts *h'' h''*. 85 The contact *k'*, also carried by the armature *k*, is moved into contact with the contact *h''*. As a consequence of the connections thus effected by the magnet *b* at station No. 1, the transmitter at station No. 1 is supplied with 90 current from battery *d* over a circuit which may be traced from the upper terminal of the battery *d* through the impedance *i* of the called line 2 2, the contact *a''*, the switch spring *a''*, the contact *h''*, the contact *h'*, the 95 telephone transmitter and receiver at calling station No. 1, the contacts *h'' h''* that are brought into connection by the switch hook *h* when relieved of the weight of the receiver, the contact *h'*, contacts *h'' h''*, the 100 winding of magnet *b*, the switch hook *h*, and the contact *h'* to the lower terminal of battery *d*. The transmitter at the called station No. 2 is supplied with current from the battery *d* by way of a circuit which may be 105 traced from the upper terminal of the battery *d* through the impedance *i* in the upper side of line 2 2, the contact *h''* normally connected with the contact *h'*, the transmitter and receiver at station No. 2, the contacts *h'' h''* at station No. 2, the receiver *g* at said 110 station being removed from its switch hook, the lower side of line 2 2, the contacts *a'' a''* of the depressed button at station No. 1, the contacts *h'' h''* at station No. 1, the winding 115 of magnet *b* at station No. 1, the switch hook *h* and the contact *h'* at station No. 1, to the lower terminal of the battery *d*. The transmitters are thus supplied with current or 120 energy, but I do not wish to be limited to the 125 130

use of common battery for the purpose of supplying the transmitters with energy. Telephonic connection between the calling and called stations may be traced for example from the transmitter at station No. 1 through the contact h^4 at station No. 1, the contact h^5 at station No. 1, the switch spring a^3 at station No. 1, the contact a^2 at station No. 1, the upper side of line 2 2, the contact h^6 at station No. 2, the contact h^4 at station No. 2, the transmitter and receiver at station No. 2, contacts h^2 h^3 at station No. 2, the lower side of line 2 2, contacts a^4 a^5 at station No. 1, contacts h^1 h^2 at station No. 1, and back to the transmitter at station No. 1. The arrangement is preferably such that the calling station may maintain the selected operating key fully depressed until the called station responds, the establishment of the signaling circuit in no wise interfering with the establishment of the telephonic circuit occurring when the party at the called station removes his receiver from its switch hook, the calling station ascertaining that the called station has heard the signal when the party at the called station speaks into his transmitter. The arrangement is also such that the continued presence of the signaling circuit in no wise interferes with the test and lockout features of my invention.

I have thus fully described how a calling station may select and signal a station that is free for selection, this result being permitted owing to the normal idle position of the armature k at the called station. I will now describe the specific means illustrated for preventing a station from having telephonic connection with either the calling station No. 1 or the called station No. 2, and whereby a busy condition is manifested at the third station.

From the drawing and the description thereof which has been furnished, it will have been observed that the switch hook contact h' at each station is in permanent connection with the lower terminal of the common battery d , and that the upper terminal of said common battery is connected with the lower side of the calling line, line No. 1, and the lower side of the line extending to the station, station No. 2, that has been called. An inspection of the drawing will show that the lower terminal of each magnet c is adapted to be connected with the lower terminal of the battery d by way of the corresponding switch hook and the contact h' when engaged by such switch hook. The upper terminal of each magnet c is connected with a contact m which is engaged by the contact spring e^4 when the bar e^3 associated with such spring is depressed, partially or fully. The contact spring e^4 at each station is permanently connected with the springs a^5 at such station, the result being that when either of the

keys at station No. 3 is fully depressed, the terminal m of the magnet c at such station is connected with the lower limb of line 1 1 or the lower limb of line 2 2 according to the key that is depressed, and through such limb with the upper terminal of the battery d , whereby the magnet c is energized to move its armature which is the same armature k that is provided for the magnet b , in a counter-clockwise direction. The contacts h' h^2 at station No. 3, instead of being closed together, are even farther separated so that the circuit including the telephone at station No. 3 is maintained open, the party at station No. 3 thus being unable to listen in upon either lines 1 1 or 2 2. A circuit is however established through the telephone apparatus at station No. 3 that includes the battery e and the circuit making and breaking magnet f , whereby a characteristic test signal is manifested in the receiver at station No. 3 to indicate to the party at said station that the line desired is busy. This circuit may be traced from the lower terminal of the battery e through the engaged contacts n at station No. 3, the telephone receiver g at said station, the telephone transmitter at said station, the engaged contacts o , the circuit making and breaking magnet f and its armature switch, to the upper terminal of the battery e . The telephone receiver g is the preferred device for responding to the testing current, but I do not wish to be limited to this device for this purpose. Testing current is thus supplied to a responsive device at a calling station seeking connection with a busy line without having such testing current impressed upon the busy line, the test circuit being purely local or preferably conductively independent of the line tested. Though the contacts e^4 m at a calling station seeking connection with a line free to be selected are engaged when the key individual to the line being selected is actuated, yet the magnet c at such station does not have circuit closed therethrough, owing to the fact that there is a gap at h^2 h^3 at the selected station, station No. 2, in the path between the magnet c and the upper terminal of the battery d . When the selected party responds, the magnet c at the calling station, station No. 1, may thereupon or thereafter be energized providing the bar e^3 is depressed, but such magnet c cannot alter the position of the armature k , which is only effectively subject to the influence of the magnet b , during the time that the calling party at station No. 1 has his telephone receiver removed from its switch hook. When the calling party restores his receiver, circuit for the magnet b is opened at h' , and since the contacts e^4 m at the calling station, station No. 1, are then separated, the arma-

ture *k* is restored to its normal neutral position, such a neutral position being indicated for the armature *k* at station No. 2. In order to prevent false operation of the magnet *c*, the plungers of the keys have a sufficient amount of lost motion with respect to the springs of the keys so that the key which is being fully depressed will occasion downward movement of the bar *e*³ to release all the other keys associated with said bar and permit the plungers thereof to be thrust to their outermost positions before the switch contacts of the key that is being operated are actuated, circuit for the magnet *c* then being most positively opened at the contacts *a*⁴ *a*⁵ of the released keys. If a party seeks a line not free for selection, his magnet *c* becomes operated in the manner which has been described, whereafter the seeking party, desiring to seek still another line, may, in the act of depressing the key at his station individual to such other line, open the circuit of his magnet *c* at the contacts *a*² *a*³ of the key individual to the line which the calling party first endeavored to select.

While I have shown keys individual to the different lines at the different stations, I do not wish to be limited thereto in the strict significance of the term, and I therefore use the term switches in the claims in a broad sense.

From the description which has been given, it will be seen that I have provided a telephone system including three or more telephone lines, each extending to the stations of the other lines, switches at each station of each of said lines individual to the remaining lines, and electro-magnetic apparatus at each of the stations governed by said switches for bringing about telephonic connection between the telephone stations of the different lines, such apparatus at the called station when in normal condition coöperating with apparatus at a calling station when actuated to permit telephonic communication between the calling and called stations.

While I have herein shown and particularly described the preferred embodiment of my invention, I do not wish to be limited to the precise arrangement shown, as changes may readily be made without departing from the spirit of my invention, but,

Having thus described my invention, I claim as new and desire to secure by Letters Patent the following:

1. A telephone system including three or more telephone lines, each extending to the stations of the other lines, switches at each station of each of said lines individual to the remaining lines, apparatus at each of the stations governed by said switches for bringing about telephonic connection be-

tween the telephone stations of the different lines; such apparatus at the called station when in normal condition coöperating with apparatus at a calling station when actuated to permit telephonic communication between the calling and called stations, and a talking battery common to said lines. 70

2. A telephone system including three or more telephone lines, each extending to the stations of the other lines, switches at each station of each of said lines individual to the remaining lines, electro-magnetic apparatus at each of the stations governed by said switches for bringing about telephonic connection between the telephone stations of the different lines, such apparatus at the called station when in normal condition coöperating with apparatus at a calling station when actuated to permit telephonic communication between the calling and called stations and a talking battery common to said lines. 80

3. A telephone system including three or more telephone lines, each extending to the stations of the other lines, switches at each station of each of said lines individual to the remaining lines, apparatus at each of the stations governed by said switches for bringing about telephonic connection between the telephone stations of the different lines, and means jointly controlled by the equipment of a busy line and the equipment of a line seeking connection with such busy line for establishing a busy test which is independent of the lines. 90

4. A telephone system including three or more telephone lines, each extending to the stations of the other lines, switches at each station of each of said lines individual to the remaining lines, apparatus at each of the stations governed by said switches for bringing about telephonic connection between the telephone stations of the different lines, and means jointly controlled by the equipment of a busy line and the equipment of a line seeking connection with such busy line for establishing a busy test circuit which is independent of the lines. 105

5. A telephone system including three or more telephone lines, each extending to the stations of the other lines, switches at each station of each of said lines individual to the remaining lines, apparatus at each of the stations governed by said switches for bringing about telephonic connection between the telephone stations of the different lines, and means governed by each switch when actuated at a calling station for establishing a busy test condition in association with the calling line and the line selected by the calling line. 115

6. A telephone system including three or more telephone lines, each extending to the stations of the other lines, switches at each station of each of said lines individual to 130

- the remaining lines, apparatus at each of the stations governed by said switches for bringing about telephonic connection between the telephone stations of the different lines, such apparatus at the called station when in normal condition coöperating with apparatus at a calling station when actuated to permit telephonic communication between the calling and called stations, and means governed by each switch when actuated at a calling station for establishing a busy test condition in association with the calling line and the line selected by the calling line. 15
7. A telephone system including three or more telephone lines, each extending to the stations of the other lines, switches at each station of each of said lines individual to the remaining lines, electro-magnetic apparatus at each of the stations governed by said switches for bringing about telephonic connection between the telephone stations of the different lines, such apparatus at the called station when in normal condition coöperating with apparatus at a calling station when actuated to permit telephonic communication between the calling and called stations, and means governed by each switch when actuated at a calling station for locking out the telephone of a line seeking the line of the calling station and the line selected by the calling station. 20
8. A telephone system including three or more telephone lines, each extending to the stations of the other lines, switches at each station of each of said lines individual to the remaining lines, apparatus at each of the stations for bringing about telephonic connection between the telephone stations of the different lines, and means governed by each switch when actuated at a calling station for establishing a busy test condition in association with the calling line and the line selected by the calling line. 25
9. A telephone system including three or more telephone lines, each extending to the stations of the other lines, switches at each station of each of said lines individual to the remaining lines, apparatus at each of the stations governed by said switches for bringing about telephonic connection between the telephone stations of the different lines, and means jointly controlled by the equipment of a busy line and the equipment of a line seeking connection with such busy line for locking out the telephone of the seeking line. 30
10. A telephone system including three or more telephone lines, each extending to the stations of the other lines, switches at each station of each of said lines individual to the remaining lines, apparatus at each of the stations governed by said switches for bringing about telephonic connection be- 35
- tween the telephone stations of the different lines, and means governed by each switch when actuated at a calling station for locking out the telephone of a line seeking the line of the calling station and the line selected by the calling station. 40
11. A telephone system including three or more telephone lines, each extending to the stations of the other lines, switches at each station of each of said lines individual to the remaining lines, apparatus at each of the stations governed by said switches for bringing about telephonic connection between the telephone stations of the different lines, such apparatus at the called station when in normal condition coöperating with apparatus at a calling station when actuated to permit telephonic communication between the calling and called stations, and means governed by each switch when actuated at a calling station for locking out the telephone of a line seeking the line of the calling station and the line selected by the calling station. 45
12. A telephone system including three or more telephone lines, each extending to the stations of the other lines, switches at each station of each of said lines individual to the remaining lines, electro-magnetic apparatus at each of the stations governed by said switches for bringing about telephonic connection between the telephone stations of the different lines, such apparatus at the called station when in normal condition coöperating with apparatus at a calling station when actuated to permit telephonic communication between the calling and called stations, and means governed by each switch when actuated at a calling station for locking out the telephone of a line seeking the line of the calling station and the line selected by the calling station. 50
13. A telephone system including three or more telephone lines, each extending to the stations of the other lines, switches at each station of each of said lines individual to the remaining lines, apparatus at each of the stations governed by said switches for bringing about telephonic connection between the telephone stations of the different lines, and means governed by each switch when actuated at a calling station for locking out the telephone of a line seeking the line of the calling station. 55
14. A telephone system including three or more telephone lines, each extending to the stations of the other lines, switches at each station of each of said lines individual to the remaining lines, apparatus at each of the stations governed by said switches for bringing about telephonic connection between the telephone stations of the different lines, such apparatus at the called station when in normal condition coöperating with apparatus at 60

a calling station when actuated to permit telephonic communication between the calling and called stations, and means governed by each switch when actuated at a calling 5 station for locking out the telephone of a line seeking the line of the calling station.

15. A telephone system including three or more telephone lines, each extending to the stations of the other lines, switches at each 10 station of each of said lines individual to the remaining lines, electro-magnetic apparatus at each of the stations governed by said switches for bringing about telephonic connection between the telephone stations of the 15 different lines, such apparatus at the called station when in normal condition coöperating with apparatus at a calling station when actuated to permit telephonic communication between the calling and called stations, 20 and means governed by each switch when actuated at a calling station for locking out the telephone of a line seeking the line of the calling station.

16. A telephone system including three or 25 more telephone lines, each extending to the stations of the other lines, switches at each station of each of said lines individual to the remaining lines, apparatus at each of the stations governed by said switches for bringing 30 about telephonic connection between the telephone stations of the different lines, and means governed by each switch when actuated at a calling station for locking out the telephone of a line seeking the line selected 35 by the calling station.

17. A telephone system including three or more telephone lines, each extending to the stations of the other lines, switches at each station of each of said lines individual to the 40 remaining lines, apparatus at each of the stations governed by said switches for bringing about telephonic connection between the telephone stations of the different lines, such apparatus at the called station when in normal 45 condition coöperating with apparatus at a calling station when actuated to permit telephonic communication between the calling and called stations, and means governed by each switch when actuated at a calling 50 station for locking out the telephone of a

line seeking the line selected by the calling station.

18. A telephone system including three or more telephone lines, each extending to the stations of the other lines, switches at each 55 station of each of said lines individual to the remaining lines, electro-magnetic apparatus at each of the stations governed by said switches for bringing about telephonic connection between the telephone stations of the different lines, such apparatus at the called station when in normal condition coöperating with apparatus at a calling station when actuated to permit telephonic communication between the calling and called stations, 60 and means governed by each switch when actuated at a calling station for locking out the telephone of a line seeking the line selected by the calling station.

19. A telephone system including three or 70 more telephone lines, each extending to the stations of the other lines, switches at each station of each of said lines individual to the remaining lines, apparatus at each of the stations governed by said switches for bringing about telephonic connection between the telephone stations of the different lines and for establishing a busy test condition and mechanism at each station governed by the 75 switches thereat for preventing false busy tests.

20. A telephone system including three or more telephone lines, each extending to the stations of the other lines, switches at each station of each of said lines individual to the 80 remaining lines, apparatus at each of the stations governed by said switches for bringing about telephonic connection between the telephone stations of the different lines and for locking out the telephone of a line seeking a busy line, and mechanism at each station governed by the switches thereat for preventing improper lockouts.

In witness whereof, I hereunto subscribe my name this 11th day of January, A. D., 95 1910.

ELMER R. CORWIN.
